UNITED STATES PATENT OFFICE.

JACOB M. HOUFF, OF MADISON, VIRGINIA, ASSIGNOR OF ONE-HALF TO PETER L. HARGETT, OF FREDERICK, MARYLAND.

SILO-BRACING SYSTEM.

1,316,895.

Specification of Letters Patent. Patented Sept. 23, 1919.

Application filed February 12, 1918. Serial No. 216,731.

To all whom it may concern:

Be it known that I, JACOB M. HOUFF, a citizen of the United States, residing at Madison, in the county of Madison and State 5 of Virginia, have invented or discovered certain new and useful Improvements in Silo-Bracing Systems, of which the following is a specification, reference being had therein to the accompanying drawings.

10 This invention relates to a system of bracing for silos or the like, and has for its object to provide a cable bracing system which will have the least possible number of joints so that the objection incidental to a multiplicity of joints will be avoided. To this 15 end the improved construction comprises what may be termed a continuous cable bracing, in that the cable runs continuously or unbroken from end to end, being looped about the devices by which it is attached to 20 the upper part of the silo, and also looped about the gripping devices connected with stays anchored into the ground at some distance outside of the base or foundation of 25 the silo. The present invention is an improvement on the silo bracing system covered by my U. S. Patent No. 1,220,227, granted March 27, 1917.

In the accompanying drawings Figure 1 30 is a plan view of a silo with the improved bracing system applied thereto. Figs. 2 and 3 are broken out elevations of the silo, from the front and back thereof, respectively, 35 illustrative of the present invention. Fig. 4 is an enlarged detail view of one of the lower gripping or holding devices and a part of its attached stay rod, looking, for example, in the direction of the arrow 4 in Fig. 3. Fig. 5 is a detail view of the gripping device shown in Fig. 4 looking in the 40 direction of the arrow 5 but with the cable in section. Fig. 6 is a detail view of a preferred form of attaching device for the upper looped parts of the cable, with the holding washer and nut omitted, and Fig. 7 is a 45 sectional view of the same with the holding washer and nut in place. Fig. 8 is a detail view of a modified form of holder for the lower looped parts of the cable.

50 The silo 12 herein illustrated may be of any usual or well-known construction and will preferably consist of a series of staves strongly held together by encircling bands or hoops 13.

55 The cable 14, by which the silo 12 is

braced or guyed, has a suitable connection at one of its ends with the silo at or near the top thereof, as the invention is herein shown, this connection being made by any suitable gripping or clamping device 15 which, in the 60 present instance, comprises a bolt 16 passing through the silo body 12, a cup-shaped member 17 adapted to receive a bight of the cable 14, a washer 18, preferably of less diameter than the top of the central recess of 65 the cup-shaped member 17, and a nut 19 which may be screwed down on the bolt 16 to clamp a bight of the cable in the said central recess of the cup-shaped member. Owing to the inwardly sloping wall of the 70 cup-shaped member 17 the bight of the cable, which when first placed in said cup-shaped member will be loose in the recess in said member, as shown in Fig. 6, will be forced inward toward the bolt 16 when the 75 nut 19 is screwed down to force the clamping washer 17 against the cable, so that the bight of the cable within said cup-shaped member will be securely gripped by this holding device. The cable may thus be 80 securely attached at one end to the silo body at or near the top thereof, and, in the construction herein shown, it runs to a lower gripping or holding device 20 which is adapted to hold a bight thereof, thence to 85 another upper holding device 15, thence to a second gripping or holding device 20, thence to a third upper holding device 15, thence to a third lower gripping or holding 90 device 20, from which it extends to a fourth upper holding device 15. It will thus be understood that the cable runs continuously 95 from its first point of attachment to the silo to its last point of attachment thereto, and therefore no splices or joints are required between the ends of the cable.

Any suitable form of gripping or holding device for the lower bights or loops of the cable may be employed, but a preferred 100 form of such gripping or holding device is shown in Figs. 4 and 5, and this gripping or holding device consists preferably of a malleable iron casting comprising a sleeve part 21 having a bracket part 22 with two open ears 23 which, when in opened-out 105 positions, as denoted in dotted lines in Fig. 5, are adapted to receive a bight of the cable loosely; but which, after the bight of the cable has been placed therein, as shown in Fig. 4, may be closed together, as shown 110

in full lines in Fig. 5, so as to tightly grip the cable. To each of the gripping or holding devices is attached a rod 24 passing through the sleeve part 21 and having a 5 threaded upper end to which is fitted a nut 25 which may be screwed down to tighten the cable 14 after the lower end of the rod 24 has been suitably anchored in the ground, outside of the base of the silo; as will be 10 understood from Fig. 3.

Instead of using the form of lower holding device 20 just described a simpler form of lower holding device, such as that shown in Fig. 8 may be employed. This modified 15 form of holding device, which may be of malleable iron or any other suitable material, comprises a sleeve portion 21^a having at one end a hooked bracket 22^a around which a lower bight or loop of the cable 14 20 may be passed, as will be understood.

From the foregoing it will be seen that the present improved silo bracing system consists of a cable running continuously from its first to its last point of attachment, 25 through suitable upper and lower holding or gripping devices, and that, intermediate of its end points of attachment, no splices or cable joints are required.

While, in the construction herein shown, 30 the ends of the cable are shown as being attached to the silo, at or near the top of the latter, it will be understood that the invention is not limited to this manner of attaching or securing the ends of the continuous cable, as the ends thereof might be 35 held by lower gripping or holding devices similar to or performing the functions of the lower gripping devices 20, and in such case will be looped around suitable upper holding or gripping devices, such, for example, as the devices 15 hereinbefore 40 described.

In the preferred embodiment of my invention herein shown it will be understood 45 (see Fig. 1) that the continuous cable has four points of attachment to the upper part of the silo, and three anchoring connections with the ground, and that said cable runs directly and alternately from the upper 50 holding devices to the lower holding devices without intermediate attachments to the silo.

The gripping or holding device herein shown, and consisting of the malleable iron sleeve 21 and the bracket 22 integral with said sleeve and having the open ears 23 55 which may be closed against parts of the cable after the latter has been laid in the recesses afforded by said open ears, is particularly well adapted for use with a continuous cable, in that this construction facilitates the looping of the cable into this open-eared gripping or holding device, as will readily be understood.

Having thus described my invention I claim and desire to secure by Letters Patent: 65

1. The combination with a silo or the like, of a bracing therefor consisting of a cable running continuously from its first to its last point of attachment, a plurality of cable holding devices at or near the top of the 70 silo, and a plurality of lower cable holding or gripping devices connecting lower bights or loops of the cable with devices anchored to the ground, said cable running directly and alternately from the upper holding devices to said lower holding devices without 75 intermediate attachments to the silo.

2. The combination with a silo or the like, provided near its top with a series of upper cable holding devices, of a bracing therefor 80 consisting of a cable attached at its ends to the silo by two of said upper holding devices and running continuously or unbroken from one to the other of said upper cable holding devices securing the ends thereof 85 to the silo, and a plurality of lower cable holding or gripping devices engaging lower bights or loops of said continuous cable, said cable having four points of attachment to the upper part of the silo and three anchoring connections with the ground. 90

3. A cable holding or gripping device, for use in connecting a bight of a silo bracing cable or guy with the ground, consisting of a malleable iron sleeve member, adapted to 95 receive an anchoring rod, and a bracket part integral therewith and having open ears adapted to receive a bight or loop of the cable and to be closed against the cable parts to grip the same. 100

In testimony whereof I affix my signature.
JACOB M. HOUFF.
